RULING-MACHINE.

1,220,350.

Specification of Letters Patent. Patented Mar. 27, 1917.

Application filed August 3, 1912. Serial No. 713,140.

To all whom it may concern:

Be it known that I, HARMON E. LINDBLADH, a citizen of the United States, residing at Boston, in the county of Suffolk and 5 State of Massachusetts, have invented a new and useful Ruling-Machine, of which the following is a specification.

The forms in which stationery is now ruled are often so complicated, with lines of 10 many different lengths, that in the use of ruling machines as heretofore organized it is necessary to pass the sheets of paper or other stock through the machine several times, thus greatly increasing the expense 15 of the operation and the length of time required for its completion. My invention permits any form, no matter how intricate, to be ruled by a single operation for each direction in which the lines traverse the 20 sheets; and provides for this purpose a simple and compact apparatus in which the change from one form to another may be readily made, and which may be operated by one not possessing a high degree of skill.

25 It consists in the elements and combinations hereinafter described in connection with a particular embodiment of the invention, and more generically pointed out in the claims.

30 In the accompanying drawings, Figure 1 is a broken side elevation of one form of my machine; Fig. 2 is a broken top plan view thereof; Fig. 3 is an enlarged vertical section on the line 3—3 of Fig. 2; Fig. 4 is a partial transverse section on the line 4—4 of Fig. 2; Figs. 5 and 6 are details in side elevation and top plan, respectively, of a controlling lever with a section of its fulcrum-shaft; Fig. 7 is a sectional detail of 35 the mounting for the pen-bar, and Fig. 8 shows on a reduced scale a sheet ruled in accordance with the arrangement of levers appearing in the preceding figures.

Similar characters designate like parts in 40 all figures of the drawings.

Journaled at their opposite extremities in a suitable supporting frame 10 are drums 11

and 12 over which operates a belt or feeding member 13, this passing above a guide-roll 14 rotatable in the frame and across a table 50 15 extending transversely of the frame. Above the drum 11 is rotatably mounted a feeding drum 16, between which and the belt the material to be operated upon is introduced from a delivery-shelf 16^a. Power 55 is applied to the feeding members through a main driving shaft 17 carrying a pulley 18 which may be rotated at the desired speed by a belt from any convenient source of power. Fast upon the shaft 17 is a pinion 60 19 meshing with a gear 20 fixed upon the spindle of the feeding drum 16. This spindle also carries a gear 64^a coöperating in turn with a gear 21 of the same diameter upon the spindle of the belt drum 11, this 65 causing the advance of the belt and periphery of the feeding drum at the same speed. To allow the driving power to be thrown off the machine, the connection between the shaft 17 and pinion 19 is through a clutch 70 22, which may be shifted by a rod 23 extending across the machine and having a handle in a convenient position to be grasped by the operator. As it may be desirable in adjusting the machine or work 75 therein to temporarily operate it by hand, a crank 24 is secured to the spindle of the drum 16 adjacent to the handle of the clutch-rod.

In standards 25, 25 rising from the opposite sides of the frame near the rear of the table 15 is a bar 26, upon which are mounted pens or ruling devices 27 of the usual construction. These are of flexible sheet metal, each having a shank 27^a by which they are 80 held in a single series transversely of the machine by a clamp 28 secured to the bar by set-screws 29^a. The points of the trough-shaped portions of the pens coöperate with the belt 13 near the center-line of the table. 85 The pens are supplied with ink of the desired color by any convenient device (not illustrated).

From the ends of the bar project spindles

29 and 30 supported in the standards 25. To enable the pen-bar to be adjusted vertically to bring it into parallelism with the belt and table the spindles are mounted in 5 blocks 31 sliding in the standards. Projecting toward one another from the blocks and from the lower portion of the standards are upper and lower alined screws 32 and 33 oppositely threaded, and each pair is engaged 10 by a correspondingly threaded nut 34. When either of the nuts is turned the bar at that end will be raised or lowered by the approach or separation of the screws; and to compensate for this travel the spindle 29 15 is threaded through its block and is pivotally connected to the bar by a transverse end-piece 35 turning in lugs 36. Upon this spindle is a hand-wheel 37 by which it may be adjusted as the blocks are raised or lowered; and to lock the threaded spindle in 20 position a nut 38 thereon may be forced into contact with the block in which it turns. Any movement which occurs at the other end of the bar is taken care of by the play 25 between the block 31 and its standard. Rotation of this spindle 29 also permits an adjustment of the bar, and consequently of the entire series of pens, transversely of the machine. When it is desired to lift and 30 lock all the pens clear of the belt, the nut 38 is loosened and the bar is raised by an arm 39 until a screw 40 threaded therethrough is above a latch 41 pivoted upon a bracket 41^a projecting from the standard of the 35 spindle 29. The latch is then turned into the path of the screw, and the bar thus holds its upwardly tilted position until it is again released by throwing back the latch.

In my improved machine I furnish means 40 for independently controlling the engagement of each pen of the entire series with the material operated upon. Extending across the machine at the rear of the pen-bar is a shaft or other support 42 fixed in 45 standards 43, 43. Upon this shaft arranged in a single series are fulcrumed controlling levers 44, each having a nearly horizontal arm 45 projecting beneath the bar 26 to a point near the forward extremities of the 50 pens. The opposite end of each lever is upwardly inclined and has a horizontal extremity 46 for contact with actuating members to be later described. There may be carried upon the shaft 42 a controlling lever for co- 55 operation with each of the pens, those which it is not desired to actively use being moved to one side out of the path of the sheets traveling through the machine. As shown, each of the levers 44 is of substantially the 60 same thickness or width laterally as, or at least not greater than, the maximum width of the corresponding pen and extends in the same direction. By this arrangement there may be imparted to each lever and pen a

movement independent of every other associated pen, however closely placed. To hold the levers which are in use in a correct relation to the pens with which they are to co-operate, the shaft 42 is provided with a series of generally V-shaped grooves 47 extending 70 about a portion of the circumference of the shaft and respectively alined with the pens. Each controlling lever has a projection, preferably furnished by a screw 48 threaded through it with a pointed end adapted to enter any one of the grooves in the shaft according to the point to which the particular lever is moved. When thus positioned and the screw turned down so that the point lies within a groove the lever is free to oscillate 75 about the shaft, resting against the underside of the corresponding pen, and when its opposite end is depressed raising the working point of said pen from the belt, this pen-movement occurring by virtue of the flexibility of its shank. It may happen that adjacent pens are to be simultaneously controlled. In this case it is unnecessary that each pen should have a lever 44. Instead 80 there may be fixed to the arm 45 of a lever 90 a contact-plate 48^a (Figs. 5 and 6) lying beneath and co-operating with a plurality of the pens.

To maintain the forward extremity of 95 each controlling lever normally in contact with its pen, there is secured to a post 49 upon the lever a leaf-spring 50, which extends over a rod 51 carried by arms 52 projecting rearwardly from the standards 43. However the levers may be situated, their 100 springs, which are bodily movable with them, will find engagement with this rod and thus be always kept under tension regardless of lateral adjustment. To enable 105 the tension of the springs to be varied, the arms 52 may be bolted to the standards through slots 52^a so that the rod 51 may be adjusted to various positions. This rod also serves as a stop for the controlling 110 levers by the contact of their upwardly inclined arms with its under side.

Journaled to oscillate in standards 53, 53 is a vertical series of shafts or supports 54, upon each of which may be variably fixed by set-screws 54^a a series of actuating arms 55. These arms are of different lengths, but those for the same shaft being of the same length, having horizontal portions 56 and vertical portions 57 which are parallel to one another upon the succeeding shafts. All of these vertical portions extend over the ends 46 of the controlling levers but clear those of the other shafts 54, so that all the arms of the various shaft groups may be freely 120 adjusted across the machine without interfering with the arms of other groups.

To impart to each shaft 54 and to each of its groups of arms 55 and corresponding

groups of levers and pens the pen-controlling movement, there is secured to each shaft 54 a driving arm 57^a extending into contact with a cam-surface 58 upon a wheel 59, the 5 number of wheels being equal to the number of shafts 54. These cam-wheels are fast upon a shaft 60, journaled in standards 61, 61 and rotated by a pinion 62 meshing with a gear 63 turning upon a stud 64 and also 10 engaging the gear 20 upon the spindle of the feeding drum 16. The stud is adjustable in a sector-shaped slot concentric with the shaft of the gear 64^a and situated in an arm 65 depending from one side of the frame. The 15 pinion 62 is made readily removable, so that by placing upon the shaft 60 pinions of various diameters and correspondingly adjusting the gear 63, the rate of travel of the cams with respect to the feeding members 20 may be varied within suitable limits. The cam-surfaces may be furnished by plates 66 situated in peripheral grooves in the wheels 59 and secured by screws 67 engaging a circumferential series of holes about the 25 wheels. By altering the extent and location of plates 66 the contour of each cam surface may be varied to properly time the lift and release of its group of actuating arms, controlling levers and pens. Spiral springs 68, 30 extending between the driving arms 57^a and a rod 69 lying across the machine, hold said arms into contact with their cam-surfaces.

The machine is equipped with the usual gate 70 which positions each sheet upon the 35 feeding belt and automatically releases it for presentation to the pens. This gate is carried by an oscillating shaft 71 mounted in bearings 72, 72. From the shaft of the gate an arm 73 projects into coöperation 40 with a cam 74 rotatable by a shaft 75, the rotary movement being imparted to the shaft by a pinion 76 and intercurrent pinion 77, the latter being fixed to the shaft 60.

The gate-arm is shown as drawn into 45 contact with the cam by a spiral spring 77^a. The working contour of the cam 74 is such that the gate is for a brief period held in the path of an approaching sheet to position it on the belt, and then is released at the correct time with respect to the cams 58 to free 50 said sheet and allow it to travel with the belt beneath the pens in accord with the lift of the pens.

The sheets to be operated upon may be so 55 cut that their adjacent edges are not truly at right angles, and to present the sheets properly it may become necessary to adjust the angle of the gate with relation to the feeding belt to cause the ruled lines to 60 become parallel with the edges of the sheets which extend in the direction of said lines. When this is done the pen-bar must be similarly adjusted, and, to prevent the lift of the pens from varying, the controlling

elements must also be correspondingly 65 changed. To enable this operation to be conveniently and accurately performed, plates 78 and 79 are mounted to slide in ways 80 at opposite sides of the frame, they being of such width that they have some lateral play in the ways. Upon these plates 70 all the standards supporting the various elements are mounted. Secured upon the plate 78 is a rack 81 and in a bracket adjacent to the rack is journaled a short shaft 75 82, carrying a pinion 83 and engaging the rack and having at its outer end a hand-wheel 84 by which it may be turned. The plate 78 may be fixed in position by a set-screw 85, passing through a slot 86 and being threaded into the frame, a nut 86^a upon the set-screw bearing upon the top of the plate. The opposite plate 79 is pivoted upon a stud 87 rising from the frame, so that the plate may swing in its guides without moving longitudinally. When it becomes necessary to adjust the gate the set-screw 85 and its nut are loosened and the hand-wheel 84 turned until the rack and pinion have shifted the plate 78 sufficiently 85 90 to give the gate the proper angle. Simultaneously with the movement of the gate all the standards at the same side of the machine will be correspondingly moved, so that the parallelism of the transverse elements of the machine will be maintained. The set-screw 85 is then tightened to fix 95 the adjustment.

To prepare my apparatus for operation, a controlling lever 44 is adjusted beneath 100 each pen or group of pens which is to be raised from the work, and the point of its screw turned down into the slot 47 of the fulcrum-shaft alined with the pen. For the machine as illustrated to rule the vertical 105 lines on the sheet A shown in Fig. 8 there will be ten of the levers actually employed. Now for each group of lines of different length, of which this sheet has five, a cam-wheel 59, shaft 54 and driving arm 57^a is utilized, with the actuating arms 55 of each shaft corresponding in number to the lines in each group. The variable cam-plates are adjusted to lift the pens through the 110 lever system at the correct times, the precise contour of these cams not appearing in the drawings. The machine having been adjusted, sheets to be ruled are placed upon the delivery-shelf and successively advanced between the belt and the feeding-drum. Upon reaching the gate they contact with its lower edge and are squared upon the belt by it, and then released by the action of the 115 gate-cam at the proper time for presentation to the pens. This time of release bears a definite relation to the period of operation of the pen-controlling cams, so that the beginning of the ruled lines will be the 120 125

proper distance from the forward edge of the sheet. As the sheets advance over the table beneath the pens, those not lifted by the controlling levers produce their lines; 5 and as the travel of the sheet continues, the passing of the cam-surfaces 58 from beneath certain of the driving arms drop other pens, which also produce their lines. Thus the 10 ruling of all the groups of lines in this direction is completed at a single operation, this continuing for each sheet delivered by the gate, the different lengths of lines being automatically controlled throughout the operation. When another form is to be ruled, 15 it is a comparatively simple matter to vary the actuating arm and controlling lever groups and their operating cams to meet the new conditions.

Having thus described my invention, I 20 claim:

1. In a ruling machine, ruling devices, a support, controlling members each of substantially the same lateral extent as a ruling device to adapt them for independent engagement with closely adjacent ruling devices, said controlling members being independently movable upon the support in their operation of the ruling devices, and means for actuating the controlling members. 25

2. In a ruling machine, ruling devices, controlling means arranged in a single series for coöperation with each ruling device, means arranged in a plurality of series for actuating the controlling means in groups, 35 and means for moving the actuating means independently of one another.

3. In a ruling machine, ruling devices, a series of controlling members, each member being adapted for coöperation with a single 40 ruling device, and a series of members for actuating the controlling members in groups, the controlling members constituting each group being independently movable in the operation of the machine with respect 45 to one another.

4. In a ruling machine, a pen, a lever coöperating with the pen and being throughout its length of substantially the same thickness as the pen, a fulcrum about which 50 the lever moves, and means for rocking the lever about the fulcrum to control the pen.

5. A ruling machine comprising a series of devices adapted to rule closely adjacent lines, controlling members mounted for 55 movement into coöperation with any ruling device of the series, and means for imparting to the members a movement to produce their controlling effect, the controlling members and moving means therefor both being 60 adapted to be closely positioned for the operation of immediately adjacent ruling devices.

6. The combination with ruling devices, of controlling means for each ruling device,

and actuating levers having fulcra independent of the controlling means and having arms coöperating with the controlling means. 65

7. In a ruling machine, movable ruling devices, a controlling member individual to each ruling device, an actuating member individual to each controlling member, and independent rotatable means for operating said actuating members in groups. 70

8. The combination with ruling devices, 75 of a controlling lever for each ruling device, and an actuating lever having plural arms coöperating with the controlling levers.

9. A ruling machine comprising a series of pens, a support extending longitudinally of the series, members adjustable along the support into contact with a particular pen and being mounted to oscillate upon the support to control the pens, an actuating member coöperating with each of said controlling members, and a support independent of the controlling members upon which the actuating members oscillate. 80

10. The combination with a series of pens, 90 of a support, a lever for each pen of the series mounted to oscillate upon the support independently of the associated levers and having an arm coöperating with the corresponding pen and also having an oppositely extending arm, and an actuating lever coöperating with each of the last-named arms. 95

11. The combination with a series of pens, 100 of a support, a lever for each pen of the series mounted to oscillate upon the support independently of the associated levers and having an arm coöperating with the corresponding pen and also having an oppositely extending arm, means for oscillating the levers coöperating with each of the last-named arms, said oscillating means being arranged in groups, and means common to each group for operating the oscillating means. 105

12. The combination with a series of pens, 110 of lifting members for coöperation with the pens, a fulcrum-shaft for the lifting members provided with circumferential grooves occupying definite positions with relation to the pens, and means carried by the lifting members for engaging the grooves. 115

13. The combination with a plurality of 120 ruling devices, of a support, controlling means for each of the ruling devices independently movable upon the support, a plurality of other supports, and actuating means for each of the controlling means mounted to move with the last-named supports in their actuation of said controlling means.

14. The combination with a plurality of 125 independently movable pens, of a support, oscillatory controlling means for the pens independently movable upon the support, a plurality of oscillatory supports, and ac-

tuating means for the controlling means mounted upon the supports and coöperating with different groups of controlling means.

15. The combination with a plurality of pens, of a support, controlling means for the pens independently movable upon the support, a plurality of other supports, actuating means for the controlling means fixed to the supports, and independent means for moving each of the last-named supports.

16. The combination with a plurality of independently movable pens, of a support, controlling means for the pens independently movable upon the support, a plurality of other supports, actuating means for the controlling means fixed to the supports, and independent means for moving each of the last-named supports.

17. The combination with a plurality of pens, of a support, controlling means for the pens independently movable upon the support, a plurality of other supports, actuating means for the controlling means fixed to the supports, and means for moving the last-named supports at different times.

18. A ruling machine comprising a bar, pens mounted thereon, a shaft, levers oscillating about the shaft and coöperating with the pens, a plurality of other shafts, arms fixed to the last-named shafts and coöperating with the levers, and means for oscillating the arm-shafts.

19. A ruling machine comprising a bar, pens movable thereon, a shaft, levers oscillating about the shaft and coöperating with the pens, a plurality of other shafts, arms fixed to the last-named shafts and coöperating with the levers, and cams acting upon the arm-shafts.

20. A ruling machine comprising a bar, pens independently movable thereon, a shaft, levers oscillating about the shaft and coöperating with the pens, a plurality of other shafts, arms fixed to the last-named shafts and coöperating with the levers, and cams of variable contour acting upon the arm-shafts.

21. A ruling machine comprising a bar, pens independently movable thereon, a shaft, levers oscillating about the shaft and coöperating with the pens, a plurality of other shafts, lever-arms and driving arms fixed to the last-named shafts, and cams coöperating with the driving arms.

22. A ruling machine comprising a bar, pens mounted thereon, a shaft, levers oscillating about the shaft and coöperating with the pens, a plurality of other shafts, arms upon the last-named shafts, means for variably fixing the arms upon the shafts, and means for oscillating said shafts.

23. A ruling machine comprising a bar, pens independently movable thereon, a shaft, levers oscillating about the shaft and coöperating with the pens, a plurality of other

shafts arranged in a vertical series, arms fixed to the last-named shafts and extending horizontally for different distances into co-operation with the levers, and means for oscillating the arm-shafts.

24. In a ruling machine, the combination with feeding means, of a series of standards mounted at opposite sides of the machine, means mounted upon the standards for operating upon the material to be ruled and including pens, lifting levers therefor, a feedgate and cams, and means connecting the standards for varying the position of all said standards at one side of the machine.

25. In a ruling machine, a plurality of pens, a support, controlling members for the pens independently movable along the support, a spring for each controlling member bodily movable therewith, and a member extending in the same direction as the support and being common to all the springs and with which they coöperate.

26. In a ruling machine, a plurality of pens, a support, controlling members for the pens independently movable along the support, a spring for each controlling member bodily movable therewith, and a member extending in the same direction as the support and with which both the springs and controlling members contact.

27. In a ruling machine, a plurality of pens, independently movable controlling members for the pens, a spring for each controlling member, a member common to all the springs with which they coöperate, and means for holding said common member in different positions with relation to the springs.

28. In a ruling machine, a plurality of pens, independently movable controlling members for the pens, a leaf-spring secured to each controlling member, and a rod extending between all the controlling members and their springs.

29. In a ruling machine, a plurality of ruling devices arranged in a series, controlling members for the ruling devices mounted for movement along the series of such ruling devices, a spring for each controlling member bodily movable therewith, and a member extending in the direction of the series of ruling devices and being common to all the springs and with which they coöperate.

30. In a ruling machine, a plurality of ruling devices arranged in a series, controlling members for the ruling devices mounted for movement along the series of such ruling devices, a spring for each controlling member bodily movable therewith, and a member extending in the direction of the series with which the springs and the controlling members coöperate.

31. In a ruling machine, a plurality of ruling devices arranged in a series, control-

ling members for the ruling devices mounted for movement along the series of such ruling devices, a spring for each controlling member bodily movable therewith, and a 5 member extending in the direction of the series of ruling devices and with which all the springs and ruling devices contact.

32. The combination with ruling devices, of a controlling lever for the ruling devices, 10 and an actuating lever having an arm coöp-

erating with the controlling lever and being fulcrumed independently thereof.

Signed at Boston, in the county of Suffolk and State of Massachusetts, this first day of August, 1912.
